LOCATION INDICATOR HAVING AN ENDLESS WEB AND SLIDING NAME PLATE TO COVER AND UNCOVER INDICATIONS ON THE WEB

George E. Graydon, Windsor, Ontario, Canada

Application April 13, 1945, Serial No. 588,195

3 Claims. (Cl. 40—96)

1

The present invention relates to new and useful improvements in devices for indicating the location of a person upon leaving his office, in order that he may be readily located when desired.

Frequently, in large offices, a person will leave the office and his immediate whereabouts will be unknown, thus causing considerable loss of time and annoyance in locating the missing person, and it is accordingly an object of the present invention to provide a changeable sign or exhibitor by means of which a person, when leaving his office, may be easily and quickly located.

More specifically, the invention embodies a changeable sign or exhibitor mounted in a cage provided with a window and under which an endless web may be moved, the web having printed thereon the names of various other offices, places or locations which a particular office worker may have occasion to visit from time to time and which may be selectively brought into position opposite the window as an indicator to others during his absence where the office worker may be found or located.

A still further object of the invention is to provide a name plate slidably mounted under the window for use by the office worker when he is at his desk.

Another object of the invention is to provide means for moving the name plate out of registry with the window by the changeable sign or exhibitor when the latter is actuated into a desired position.

Another object is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view.

Figure 2 is a longitudinal sectional view taken substantially on a line 2—2 of Figure 1.

Figure 3 is a transverse sectional view taken substantially on a line 3—3 of Figure 2.

Figure 4 is a plan view of the name plate.

Referring now to the drawing in detail, where for the purpose of illustration I have disclosed a preferred embodiment of the invention, the numeral 5 designates a base having a relatively short

2

upstanding wall 6 on its upper surface and inwardly of the marginal edges thereof.

A raised cover 7 has its lower edges resting on the base 5 in snug fitting engagement outwardly of the wall 6 to form a case within which a pair of rollers 8 are journaled by means of shafts 9, the rollers having an endless web 10 arranged to travel thereon. One end of one of the shafts 9 is provided with a manipulating knob 11 to rotate one of the rollers whereby to move the web thereon.

The top of the case 7 is provided with a window 12 and the surface of the web 10 has printed or otherwise displayed thereon the names of various departments of an office, factory or the like, such as indicated at 13, adapted to be successively moved into registry beneath the window 12 by the manipulation of the knob or handle 11.

A name plate 14 has its side edge portions 20 slidably mounted in channeled guides 15 at the sides of the case 5 for movement of the name plate into and out of position under the window 12, the name plate being manipulated by means of a handle 16 extending upwardly therefrom 25 through a slot 17 in the top of the case.

A protuberance or lug 18 extends downwardly from the under side of the name plate 14 into a position for engagement by the upper surface of the web 10, so that upon a rotation of the rollers 8 in one direction by the knob or handle 11, the movement of the web 10 will slidably actuate the name plate 14 in a direction to move the latter out of registry with the window 12 and thus expose the name 13 appearing on the surface of the web.

The name plate 14 has the name of a person printed or otherwise displayed thereon, as indicated at 19.

In the operation of the device, when an office worker is occupying his desk, the name plate 14 is moved into a position in registry with the window 12, whereby the name of the person will be exposed to view therein. When such person leaves his desk and expects to be absent for an indefinite period, in another part of the office or factory, the knob or handle 11 is rotated in a direction to slide the name plate 14 out of registry with the window opening 12 into the position as shown in Figure 2 of the drawing and 50 to also bring into position in registry with the opening 12 the name of the department or other location where he may be found during his absence from his desk, and accordingly other persons in the office may then be informed 55 where the absent person may be located.

It is believed the details of construction, manner of operation and advantages of the device will be readily understood from the foregoing without further detailed explanation.

Having thus described the invention, what is claimed is:

1. A changeable sign comprising a case including a base, a window in the top of the case, a traveling member in the case having indicia displayed thereon for movement into and out of registry under the window, a name plate mounted for sliding movement in the case between the window and the traveling member, and means operatively connecting the name plate to said traveling member for actuating said plate upon movement of said traveling member.

2. A changeable sign comprising a case including a base, a window in the top of the case, a traveling member in the case having indicia displayed thereon for movement into and out of registry under the window, a name plate mounted for sliding movement in the case between the window and the traveling member, and friction engaging means between the name plate and the traveling member and adapted to move the name plate out of registry with the window upon a

movement of the traveling member in one direction.

3. A changeable sign comprising a case including a base, a window in the top of the case, a traveling member in the case having indicia displayed thereon for movement into and out of registry under the window, a name plate mounted for sliding movement in the case between the window and the traveling member, manually operable means for moving the name plate into and out of registry with the window, a friction engaging means between the name plate and the traveling member for actuating the former upon a movement of the latter.
